UNITED STATES PATENT OFFICE.

GORDON E. ROEDDING, OF GRAND RAPIDS, MICHIGAN, ASSIGNOR TO DOERR MANUFACTURING COMPANY, OF GRAND RAPIDS, MICHIGAN, A CORPORATION OF MICHIGAN.

CONTAINER.

Application filed November 24, 1924. Serial No. 751,833.

To all whom it may concern:

Be it known that I, GORDON E. ROEDDING, a citizen of the Dominion of Canada, residing at Grand Rapids, in the county of Kent and State of Michigan, have invented new and useful Improvements in Containers, of which the following is a specification.

The present invention relates to containers; and its object is to provide an improved device of that character having a receptacle which may be readily swung to open and to closed positions, and may be securely held in its closed position; and further, to provide such a swingably-mounted receptacle having means for yieldably holding the same in its open position.

This, and any other and more specific objects hereinafter appearing are attained by, and the invention finds preferable embodiment in, the device hereinafter particularly described in the body of this specification and illustrated by the accompanying drawings, in which:

Figure 1 is a view in perspective of a container in closed position;

Figure 2 is a like view of the same in open position;

Figure 3 is a view in perspective of the frame or casing of the container;

Figure 4 is a view in perspective of the receptacle of the device;

Figure 5 is a view in perspective of a member slidably mounted on said receptacle;

Figure 6 is a sectional view of the entire device taken on a central transverse vertical plane, and showing the same in closed position;

Figure 7 is a like view of the same, but showing the device in open position; and

Figure 8 is a like view of certain parts of the same, but showing a modified construction.

In the embodiment of the invention illustrated by the drawings, a container for cigarettes, matches and the like adapted to be mounted in the interior of an automobile is shown. This device comprises a frame or casing 1 having an open front 2, and secured in position by suitable means as by screws passing through openings 3 in the casing's end walls 4. A receptacle 5, adapted to hold boxes and articles as seen in Figure 2, is swingably mounted at its lower outer edge on the casing frame, as by means of its tongues 6 inserted into sockets 7 adjacent

the casing's lower front edge. This receptacle carries a member 8 vertically slidable thereon in bearings provided by said member's bent-over clips 9 containing slidably the side edges of the front leaf 10 of the receptacle. This member 8 has inwardly extending side wings 11 carrying at their upper inner corners bent-over lugs or parts 12. The end walls 4 of the casing 1 are provided with slots 13 forming guide-bearings in which the lugs or parts 12 of the member 8 are adapted to move slidably. This slide-bearing comprises a vertical portion 14 which serves as a keeper, receiving the parts or lugs 12 in the receptacle's closed position 70 and thus holding the same securely closed; this slide-bearing also comprises a portion 15 extending laterally from the keeper portion 14 of the slide-bearing and toward the front of the device, the outer end 16 of this 75 lateral portion forming a stop to limit the outward or opening movement of the receptacle. A spring 17 pressing between a shelf 18 on the receptacle and an overhang 19 on the member 8 presses this member upwardly, thus urging the lugs or parts 12 into the vertical keeper portion of the guide-bearing when the receptacle is swung to its closed position. When however the member 8 is pressed downwardly by its handle 20 to 80 open the receptacle, the lugs or parts 12 pass below the elbow 21 in the guide-bearing and may be drawn by the opening movement of the receptacle into the lateral portion 15 of said bearing, and may slide there-along until 90 the end of said portion, the stop 16, is reached, so that the receptacle is thus limited to the open position seen in Figure 2. In the construction shown in Figures 1, 2, 3, 6 and 7 this lateral portion 15 of the slot or 95 guide-bearing is an arc of the circle whose center is the axis of the receptacle's swingable mounting; but in the modified construction shown in Figure 8, this lateral portion 15¹ of the guide-bearing extends from 100 the elbow 21 in a direction increasingly distant from said axis, so that the spring urges the receptacle to open position whenever the lugs or parts 12 are in said lateral portion 15¹ of the guide-bearing. The position of 105 the lateral portion 15 in other views relatively to the position of the lateral portion 15¹ is shown in dotted lines in Figure 8.

It will be seen that the member 8, when the receptacle is swung into the casing and the 110

lugs or parts 12 enter the vertical keeper portion 14 of the guide-bearing, is pressed upwardly by the spring to a position closing the open upper portion of the casing's front, 5 as seen in Figure 1.

As shown in Figures 6, 7 and 8, the device 10 may be so mounted, that the casing frame extends into a wall 25, the flange 26 of the casing frame resting on the wall's outer

15 surface. The invention being intended to be pointed out in the claims, is not to be limited to or by details of construction of any particular embodiment thereof illustrated by 15 the drawings or hereinbefore described.

I claim:

1. In a device of the character described: a frame; a receptacle swingably mounted thereon and having a slideable member provided with a guided keeper-engaging part, 20 the frame having a guide-bearing comprising a keeper portion and a portion extending laterally therefrom, said member's said part being guidedly movable in the bearing and into its keeper portion to hold the receptacle in closed position.

2. In a device of the character described: a frame; a receptacle swingably mounted thereon and having a slideable member provided with a guided keeper-engaging part, 30 the frame having a guide-bearing comprising a keeper portion and a portion extending laterally therefrom, said member's said part being guidedly movable in the bearing and into its keeper portion to hold the receptacle in closed position; a spring pressing said member to slide its said part into the keeper portion.

3. In a device of the character described: a frame; a receptacle swingably mounted 40 thereon and having a slideable member provided with a guided keeper-engaging part, the frame having a guide-bearing comprising a keeper portion and a portion extending laterally therefrom in a direction in- 45 creasingly distant from the axis of the receptacle's swingable mounting, said member's said part being guidedly movable in the bearing and into its keeper portion to hold the receptacle in closed position; a 50 spring pressing said member to slide its said part into the keeper portion and from said axis.

4. In a device of the character described: an open-front casing frame; a receptacle 55 mounted thereon swingably to a position therein and having a member slideable on the receptacle to casing-closing position and provided with a guided keeper-engaging part, the casing frame having a guide-bearing 60 comprising a keeper portion and a portion extending laterally therefrom in a direction increasingly distant from the axis of the receptacle's swingable mounting and having a stop, said member's said part being guidedly 65 movable in the bearing, into its keeper portion to hold the receptacle in inwardly swung position, and against the stop to hold the same in outwardly swung position; a spring pressing said member to slide its said 70 part into the keeper portion and from said axis.

In testimony whereof I have hereunto set my hand at Grand Rapids, Michigan, this 22nd day of November, 1924.

GORDON E. ROEDDING.
